UNITED STATES PATENT OFFICE.

LEONARD F. FULLER, OF SAN FRANCISCO, CALIFORNIA, ASSIGNOR, BY MESNE
ASSIGNMENTS, TO THE UNITED STATES OF AMERICA.

RADIOTELEGRAPHY.

1,365,977.

Specification of Letters Patent. Patented Jan. 18, 1921.

Application filed June 18, 1917. Serial No. 175,298.

To all whom it may concern:

Be it known that I, LEONARD F. FULLER, a citizen of the United States, and a resident of the city and county of San Francisco and State of California, have invented certain new and useful Improvements in Radiotelegraphy, of which the following is a specification.

The invention relates to means of signaling and particularly to means for signaling with arc radio transmitters.

An object of the invention is to provide means for signaling involving interrupting and reestablishing the arc.

Another object of the invention is to provide unitary means for successively establishing and interrupting the arc.

The invention possesses other advantageous features, some of which, with the foregoing, will be set forth at length in the following description, where I shall outline in full that form of the invention which I have selected for illustration in the drawings accompanying and forming part of the present specification. It is to be understood, however, that the invention as expressed in the claims is not limited to the specific embodiments shown in the drawings.

Referring to said drawings:

Figure 1 is a diagrammatic representation of one form of the system which is particularly applicable for low powered stations.

Fig. 2 is a diagrammatic representation of a modification of a portion of the system to adapt it to high powered stations.

Fig. 3 is a diagrammatic representation of another modification.

My present invention provides a means of signaling which contemplates opening and closing the antenna circuit. Opening the antenna circuit extinguishes the arc and means are provided for reigniting the arc as the antenna circuit is closed.

The transmission system comprises an arc oscillation generator 2 which is grounded on one side, preferably the negative and connected on the other side to the antenna 3 through the variable antenna inductance 4. Direct current is supplied to the arc generator, by the generator 5, and a choke coil 6 is arranged in the lead 7 connected to the antenna side of the arc. The arc is subjected to a strong transverse magnetic

field produced by the magnet coils 8 arranged in the lead 7.

Arranged between the arc and the antenna are contacts 9 and 11, the contact 11 being mounted on a lever 12, so that it is readily movable to open and close the antenna circuit. The lever is normally held in position to open the circuit by a spring 13. The lever may be directly connected to a sending key or it may be operated by other suitable means, such as the solenoid 14 arranged in a local circuit with a key 15 and battery 16. When the key is closed, the antenna circuit is closed and when the key is opened, the spring 13 opens the antenna circuit.

The potential of the generator 5 and the inductive kick of the inductance of the magnetizing windings is usually not sufficient to reignite the arc, after the antenna circuit has been opened and supplementary means are provided for reigniting the arc. Connected across the arc is a spark circuit containing the spark gap 17, the secondary of the transformer 18 and the capacity 19, 80 shunting the secondary. A stopping resistance 21 is arranged between the spark gap and the antenna side of the arc to prevent sufficient direct current to maintain an arc across the spark gap and the high frequency current from passing through the secondary. The primary of the transformer is in series with an alternating current generator 22 and a switch 23 which is attached to the lever 12. When the antenna 90 circuit is closed, the circuit through the primary of the transformer is closed, producing a high potential in the spark circuit and producing a spark across the spark gap which sets up radio frequency surges which 95 ignite the main arc.

In this arrangement, the current in the magnetizing windings varies, and while this feature is deleterious in large stations on account of the large inductance of the magnetizing windings, it does not seriously interfere with the operation of small stations.

In order to maintain the current in the magnetizing winding constant, as the arc is extinguished and ignited, a separate generator 24 is arranged in shunt with the magnetizing winding as shown in Fig. 2. This generator is chosen so that its E. M. F. equals the product of the resistance of the winding by the normal current flowing there-

through when the arc is burning. When the arc is burning, the field is excited by current from the generator 5 and when the arc is extinguished, the field is excited by current from the generator 24.

In Fig. 3 I have shown a separately excited magnetic field, the magnetizing winding 8 in this instance being in series with the generator 25 and independent of the arc circuit. The constructions shown in Figs. 2 and 3 are particularly adapted for high powered systems in which the inductance of the magnet windings is great, but in systems of small power, the apparatus shown in Fig. 1 may be advantageously employed.

I claim:

1. An arc system for radio signaling, comprising an arc, a current supply and antenna circuit connected to the arc, means for opening and closing the antenna circuit and means operative simultaneously with the closing of the antenna circuit for igniting the arc.
2. An arc system for radio signaling comprising two normally stationary electrodes, between which an arc is formed, a current supply connected to the arc, a normally open antenna circuit connected to the arc, and means operative in time with the closing of the antenna circuit for igniting the arc.
3. An arc system for radio signaling comprising two normally stationary electrodes between which an arc is formed, a current supply connected to the arc, a normally open antenna circuit connected to the arc, and means operative in time with the closing of the antenna circuit for producing an ignition spark across the arc.

4. An arc system for radio signaling comprising an arc, a current supply connected to the arc, a normally open antenna circuit connected to the arc, a spark circuit shunted around the arc and adapted to produce an ignition spark across the arc as the antenna circuit is closed and means for closing the antenna circuit.

5. An arc system for radio signaling comprising an arc, a current supply connected to the arc, an antenna circuit connected to the arc, a switch in the antenna circuit, a spark circuit shunted across the arc, a switch controlling said spark circuit and means connecting said switches whereby they are closed substantially simultaneously.

6. An arc system for radio signaling comprising an arc, a current supply connected to the arc, a magnet winding for producing a transverse field on said arc, a current supply connected across the magnet winding, an antenna circuit connected to said arc, means for opening and closing the antenna circuit and means operative simultaneously with the closing of the circuit for igniting the arc.

7. An arc system for radio signaling comprising an arc, a current supply and antenna circuit connected to the arc, means for opening and closing the antenna circuit, the said means when opening the circuit serving to extinguish the arc and means for reigniting the arc.

In testimony whereof, I have hereunto set my hand at San Francisco, California, this 6th day of June, 1917.

LEONARD F. FULLER.
